UNITED STATES PATENT OFFICE

EDWARD P. HUTTGER, OF PHILADELPHIA, PENNSYLVANIA, ASSIGNOR OF ONE-HALF TO
ALEXANDER J. GIBSON, OF PHILADELPHIA, PENNSYLVANIA

WINDOW FRAME AND SASH CONSTRUCTION

Application filed August 28, 1930. Serial No. 478,372.

My invention relates to improvements in window frame and sash construction and in means for supporting the sashes in their frames, and is adapted particularly for employment in a metal double-hung window comprising a pair of sashes vertically slideable in their frame and maintained in the desired vertical position therein with the aid of suitable counterweights.

It has heretofore been the practice in the metal double-hung window art to provide a counterweight adjacent each side of each of the sashes and respectively secured thereto by a flexible chain, cable or the like extending over a sheave in the top of the frame, whereby each counterweight is effective to counterbalance, and thereby support, approximately one-half the weight of the sash to which it is secured, the guides for retaining the sashes usually comprising grooves running substantially the length of the window frame and interconnected through a chamber in the latter or otherwise. In such construction, however, the passage of air through and between the portions of the grooves unoccupied by the sashes and thus from one side of the window to the other is substantially unavoidable.

My invention therefore comprises means whereby a metal double-hung window may be made substantially airtight, that is, so arranged that the guideways provided for the respective sashes are not interconnected whereby there can be substantially no leakage from one side of the window to the other.

Additionally, I have provided by my invention means whereby the respective sashes in a double-hung window are each supported individually from one of the frame members and I am thus able to employ but a single counterweight for each sash so that the sash supporting and counterbalancing mechanisms for the respective sashes may each be separately enclosed within one of the frame members and thus made substantially independent of the other, although it will of course be understood that a guide is provided in the opposite side frame member for each of the sashes.

A principal object of my invention there-

fore is to provide a window sash and frame construction of the class described in which leakage of air from one side of the window to the other and thence into the building is substantially avoided.

A further object of my invention is to provide in a metal window sash and frame construction, means whereby the respective sashes may be afforded vertical support substantially entirely from one lateral edge thereof and the mechanism necessary for this purpose may therefore be disposed in one, only, of the lateral frame members, the other lateral frame member being employed solely as a guide for the sash; one of the sashes is therefore, in my preferred construction, supported by mechanism disposed in one of the lateral frame members and the other sash supported by similar mechanism disposed in the other of the frame members.

A further object of my invention is to provide means whereby the respective sashes may be prevented from falling when, for example, their supporting mechanisms become non-operative through breakage or for any other reason.

A still further object of my invention is to provide a double-hung window in which the sashes may be more readily slideable, and the window therefore more easily opened and closed than those which have heretofore been devised.

Other purposes, objects and advantages of my invention will hereinafter be more specifically pointed out or will appear from the following description of certain forms thereof, reference being had to the accompanying drawings.

In the said drawings, Fig. 1 is a fragmentary front elevation of a double-hung window constructed in accordance with a preferred embodiment of my invention, certain parts being broken away for the sake of clearness; Fig. 2 is a composite horizontal section of the construction shown in Fig. 1, although I have indicated no section lines therein for the reason that the view shown in Fig. 2 comprises sections taken on several different planes; Fig. 3 is a horizontal section corresponding to the left hand end of Fig. 2 and

showing a slightly modified construction, and Fig. 4 is a fragmentary detail in vertical section showing one of the sash bearings and certain other parts in elevation. In the several figures like characters are used to designate the same parts.

Referring now more particularly to the drawings, the window frame and sash construction as shown in Fig. 1 comprises an upper or outer sash 1, and a lower or inner sash 2, arranged for vertical movement between the lateral frame members 3, 4, said movement being limited by the lintel 5 and sill 6. The members 5 and 6 may be of any usual or desired construction, and the particular arrangement thereof forms no part of the present invention. The lateral frame members 3, 4 are in general substantially similar but reversed in arrangement, and each comprises a vertically extending hollow chamber 7 within which the counterbalancing mechanism is disposed. The frame member 3 at the left hand side of the window as viewed in Figs. 1 and 2 comprises a metal housing, which may be suitably formed to give an attractive appearance, and is provided on its inner face with a vertically extending guide strip 9 of section substantially as indicated in Fig. 2; this strip is preferably formed of relatively heavy steel and secured at its respective ends to the lintel and sill. The guide strip 9 is provided with a flange 10 extending longitudinally thereof which is disposed adjacent and parallel to the inturned flange 11 of the housing whereby a vertically extending guideway is formed between the flanges 10 and 11 of a width sufficient to accommodate the marginal portion of the upper sash 1 which is inserted therein. The guide strip is also provided with a channel guideway 13 adapted to receive the marginal portion of the lower sash 2 and with a rib or flange 14 to insure desired rigidity of the strip. A plate 15 forming a part of the inner wall of the frame member 3 is removably secured to the strip 9 by means of the screws 16 and is held in place at the inside corner of the frame member by means of an interlocking conformation of their respective edges, as clearly shown in Fig. 2.

In the window construction which I have indicated in Figs. 1 and 2, the outer or upper sash 1 is adapted to be supported from mechanism enclosed within the frame member 3. This sash comprises the laterally spaced glazing channel members 17, 18, the former of which extends through the guideway between the flanges 10, 11 and the latter of which is received in a suitable channel 19 in the frame member 4, the said guideway and channel providing guides for the vertical movement of the sash. Within the frame member 3 I dispose a plate 20, nuts 21 being preferably welded thereto in registry with holes through the plate and through the inner portion of the

glazing strip 17; these nuts are adapted to receive cap screws 22 whereby the plate 20 is removably secured to the glazing member 17. If desired, bronze or other relatively soft metal weather stripping W may be secured to the sashes or to the frame in any convenient way.

Adjacent the inner edge of the plate 20 relatively near the top thereof and secured thereto by welding or otherwise as desired, is a strap 24, and between the latter and the plate 20 is disposed a roller 25 mounted for rotation on a shaft 26; this roller may desirably be the outer race of a ball or other antifriction bearing carried by the shaft. A locking cam 27, desirably provided with teeth on its camming surface, is also disposed within the strap and supported on a squared shaft 28 on the protruding end of which a lug 29 is secured as by a driving fit, a pin 30 being provided as additional security against rotation of the lug 29 on the shaft which is, of course, made cylindrical where it bears in the plate and strap. Between an outwardly extending arm 31 on the cam 27 and a convenient point on the plate 20 is extended a coil spring 32 operative to urge the cam to rotate in a counter-clockwise direction as viewed in Fig. 1. Adjacent the lower end of the plate 20 I provide a similar but shorter strap 35 adapted to support a similar roller 36.

A channel rail 37 is secured, preferably by welding, to the inside of the outer face of the frame member 3 and the respective longitudinal ribs thereof provide ways along which the rollers 25 and 36 operate when the sash is moved vertically in the frame, thus enabling it to be readily raised or lowered without jamming or sticking, and with but a minimum of friction.

Adjacent the top of the frame member 3 I provide the usual pulley or sheave 38 over which is run a tension element 39, which may be a chain, cable or the like, secured at its opposite ends respectively to the lug 29 on the sash and to a counterweight 40 disposed in the chamber 7 in the frame member, the weight being substantially effective to counterbalance the sash and associated parts to permit them to be moved either up or down relatively easily and ordinarily to prevent the sash from falling when it is placed in the desired position.

As the lug 29 and the cam 27 are secured together in non-rotatable relation the spring 32 is ordinarily held extended by the tension of the chain or cable 39 on the lug 29, but if the pull of the cable on the lug 29 is released as, for example, by breakage of the cable, the spring 32 is effective to rotate the cam 27 very rapidly and thus bring its serrated face into immediate engagement with the channel rail 37, the teeth insuring a biting contact and preventing slipping of the cam; the sash is thereby prevented from falling and immedi-

ately locked substantially in the position formerly held when it was being supported by the cable before breakage of the latter. It will be noted that the sole duty of the 5 spring 32 is to rotate the cam, after breakage of the cable, sufficiently to bring its serrated face into engagement with the channel rail; thereafter the downward movement of the window progressively increases the jamming 10 action between the cam and the rail until the window is brought to rest.

I have hereinabove described particularly the left hand portion of the sash construction shown in Figs. 1 and 2, and as related especially to the outer sash 1, but it will be readily understood from the drawings that substantially similar means for supporting the inner sash 2 are provided in the right hand frame member 4 and it is believed that no additional 20 description thereof is required inasmuch as these constructions are substantially identical except for certain differences necessitated by the different relation of the sash and the frame. Thus it will be noted that the guide 25 strip 9 may be omitted entirely and the channel 19, generally corresponding to the channel guideway 13, formed directly in the body of the frame member, while the plate 20 is offset in the opposite direction from the corresponding 30 plate on the other side so as to bring the rollers 25 and 36 into proper relation with the adjacent channel rail.

In Fig. 3 I have shown a somewhat modified embodiment of my invention in which 35 vertical sash guides 10', 13', outside the frame members, are provided by welding spaced strips onto the face of the frame member, but otherwise the structure is substantially the same as that shown in Fig. 2 and, it is 40 believed, requires no further description.

While I prefer to utilize the channel rails 37 and rollers 25 and 36 for cooperation therewith, under certain circumstances I may 45 employ pipes or rods in lieu of the former and vertically spaced sleeves or yokes slideable thereon in lieu of the rollers, or substitute for the rollers suitable slide blocks adapted to move in the channel rails, as will be 50 readily understood.

From an inspection of Figs. 2 and 3 it will be understood that while in the sash and window construction of my invention the inner chamber in the left hand frame member 55 3 in which the mechanism supporting the outer sash is enclosed, is open to the atmosphere outside the building through the unoccupied portion of the guideway between the flanges 10, 11, this chamber is otherwise 60 completely enclosed when in operative assembly and therefore no air can leak into the building, even though it may pass through the unoccupied portion of the said guideway. It will also be understood that the groove 19 65 on the outside of the frame member 4 is not

in any way in communication with the interior of the frame member and no leakage of air into the building through the unoccupied portion of this guideway is possible adjacent the right hand side of the window as viewed 70 in Fig. 2, so that the window is equally leak-proof on this side as well, as it will of course be apparent that the interior of the chamber in the frame member 4, while in communication with the inside of the building through 75 the guideway provided for the lower sash is entirely sealed against entrance of air from outside the building.

Furthermore, access to the interior of either frame member may readily be obtained 80 by taking off the plate 15, and the plates 20 may thus be disconnected from their respective sash by removal of the cap screws 22 with the aid of an ordinary screw driver. The outer sash 1 may thus be readily removed 85 from the frame since the guideway between the flanges 10 and 11 is desirably of sufficient width to permit the sash, when thus released from the plate 20, to be moved laterally thereinto a sufficient distance for the member 18 to 90 clear its guideway 19 and then be swung outwardly far enough to clear the outer edge of the frame member 4, whereupon the sash may be slipped laterally away from the frame member 3. Likewise, as in the right hand 95 frame member 4, the plate 15 is readily removable, permitting access to the cap screws 22 on the inner sash and to other parts of the mechanism supporting it, and that sash may with equal facility be removed from the frame 100 in a generally similar way.

Moreover, due largely to the preferred employment of vertically spaced antifriction bearings and the utilization of but a single counterweight for each sash, a window 105 constructed in accordance with my invention may be more readily opened and closed and thus is much more satisfactory in practical use than windows heretofore employed, while many advantages in structural details 110 and ease and cheapness of manufacture will be apparent to those familiar with the art.

While I have herein described and illustrated with considerable particularity certain 115 embodiments of my invention, it will be understood that I do not thereby desire or intend to limit or confine myself specifically thereto, as many changes and modifications in the design, construction, and arrangement of the several parts and elements thereof will readily occur to those skilled in the art and may be made without departing from the spirit and scope of the invention as defined in the appended claims, while the use of the invention 120 is not confined to windows embodying metal sash and frame members although particularly advantageous under such circumstances.

Having thus described my invention, I 130

claim and desire to protect by Letters Patent of the United States:

1. In a window frame and sash construction comprising a vertically disposed frame member and a sash, a counterweight disposed in the frame member, a channel rail disposed within said member, and means cooperative with the counterweight and the rail to afford vertical support to said sash.
2. In a window frame and sash construction, a frame member, a channel rail carried thereby, a pair of spaced rollers operatively disposed within said channel rail, a window sash, means connecting the rollers and the sash, and a counterweight operatively associated with said connecting means and adapted to substantially counterbalance said sash and associated parts.
3. In a window frame and sash construction, a rotatable shaft carried by one of the sashes, a lug supported on the shaft in non-rotatable relation thereto, a tension member secured to said lug and operative to normally support said sash, a cam carried by said shaft and in non-rotatable relation with said lug, a rail carried by the frame, and a spring operative to urge said cam into engagement with said rail upon failure of the tension member to support the sash.
4. In a window frame and sash construction, a locking cam carried by one of the sashes, means adapted for engagement by the cam, a lug secured in non-rotatable relation to the cam, a counterweight disposed in one of the frame members, tension means interconnecting said lug and said counterweight whereby said cam is normally maintained in non-operative position, and means operative upon release of said tension means to move the cam into engagement with said first mentioned means to lock the sash against downward movement in the frame.
5. A window frame construction comprising a pair of sashes, a pair of vertical frame members enclosing hollow chambers, a guideway in each of said frame members communicating with the adjacent chamber, guiding means carried by each of said frame members opposite the guideway in the other member, each of said sashes being extended into one of said guideways and into one of said guiding means respectively at its opposite edges, and means adjacent each of the guideways for affording the sole vertical support to the sash extending therein.
6. In a window frame and sash construction, a vertically extending frame member having a guideway affording communication with the interior thereof, a sash having an extension projecting into the guideway, a vertically extending rail within the member, means carried by the sash extension and cooperative with the rail for maintaining the sash in substantially horizontal position throughout its range of the vertical move-
- ment, and a counterweight interconnected with the sash for substantially counterbalancing the weight thereof.
7. In a window frame and sash construction, a vertically extending frame member having a guideway affording communication with the interior thereof, a sash having an extension projecting into the guideway, a vertically extending rail within the member, means carried by the sash extension and cooperative with the rail for maintaining the sash in substantially horizontal position throughout its range of the vertical movement, a counterweight interconnected with the sash for substantially counterbalancing the weight thereof, and means carried by the opposite frame member forming a guide for the adjacent edge of the sash.
8. A window frame and sash construction comprising a pair of laterally spaced, vertically disposed frame members, each of said members having a guideway extending through its wall and communicating with its interior, a vertically extending channel rail disposed within each member adjacent the guideway, a pair of sashes disposed between the members and provided with extensions respectively projecting through the guideways in the frame members, rollers disposed adjacent the upper and lower ends of each extension and cooperative with the adjacent channel rail to maintain the sash in substantially horizontal position throughout its range of vertical movement, a counterweight within the adjacent member, and means connecting the counterweight and the extension to thereby substantially counterbalance the weight of the sash.
9. A window frame and sash construction comprising a pair of laterally spaced, vertically disposed frame members, each of said members having a guideway extending through its wall and communicating with its interior, a vertically extending channel rail disposed within each member adjacent the guideway, a pair of sashes disposed between the members and provided with extensions respectively projecting through the guideways in the frame members, rollers disposed adjacent the upper and lower ends of each extension and cooperative with the adjacent channel rail to maintain the sash in substantially horizontal position throughout its range of vertical movement, a counterweight within the adjacent member, means connecting the counterweight and the extension to thereby substantially counterbalance the weight of the sash.
10. In a window frame and sash construction, a vertically disposed frame member, a sash comprising means extending into the

frame member, a track within the member, and means carried by said first mentioned means and engaging the track at vertically spaced points operative to maintain the sash in substantially horizontal position throughout its range of movement with respect to the frame member.

In witness whereof I have hereunto set my hand this 27th day of August, 1930.

EDWARD P. HUTTGER.
